CLOTHES-WASHING MACHINE

George P. Castner, Webster City, Iowa

Application December 19, 1949, Serial No. 133,900

7 Claims. (Cl. 68—21)

1

The present invention relates to clothes washing machines, and more particularly to improved clothes washing machines of the character of that disclosed in the copending application of George P. Castner, Serial No. 124,869, filed November 1, 1949.

Fundamentally, the clothes washing machine disclosed in the Castner application mentioned comprises a tub including upstanding front and rear end walls and a connecting tubular side wall, and an upstanding flexible diaphragm arranged in the tub and secured about the perimeter thereof to an intermediate portion of the side wall, the diaphragm being movable from a normal concave position disposed adjacent to the rear end of the side wall and the rear end wall to an operated convex position disposed adjacent to the front end of the side wall and the front end wall. The diaphragm in its concave position cooperates with the front end of the side wall and the front end wall to define a compartment therebetween adapted to contain clothes and cleansing liquid, and the front end of the side wall has an opening formed in the upper portion thereof rendering the compartment accessible from the exterior, a door being provided that is mounted for movements between opened and closed positions with respect to the opening. Also the diaphragm cooperates with the rear end of the side wall and the rear end wall to define a chamber therebetween adapted to receive liquid under pressure. An upstanding perforated wall is arranged in the front of the compartment adjacent to the front end wall and spaced rearwardly with respect thereto to define an upstanding space therebetween, a drain conduit being provided that communicates with the lower portion of the compartment in the upstanding space noted. An upstanding substantially disk-like dasher is arranged in the front of the compartment adjacent to the perforated wall and mounted upon the front end wall for operation. The dasher is operated by rotation thereof unidirectionally in order to produce a washing action upon the clothes in the compartment, and the diaphragm when moved from its normal position into its operated position produces a squeezing action upon the clothes in the compartment in order to express the cleansing liquid therefrom, the clothes being squeezed between the diaphragm and the perforated wall and the dasher.

Further, the machine comprises an electric drive motor, a liquid pump, first clutch mechanism disposed between the motor and the dasher, second clutch mechanism disposed be-

2

tween the motor and the liquid pump, valve mechanism, and an electric control network. The electric control network is selectively controllable to effect selective engagement and disengagement of the clutch mechanisms and to effect selective settings of the valve mechanism so that the dasher may be selectively operated and so that liquid may be pumped into or out of the chamber in order to bring about selective movements of the diaphragm between its normal and operated positions. In the arrangement, ordinary tap water is employed as the liquid or hydraulic medium for controlling the movements of the diaphragm.

10 While this machine is highly satisfactory in operation, the amount of tap water that is required to control the movements of the diaphragm to carry out the wash water and rinse water extracting operations therein renders the over-all operation of the machine somewhat more expensive than is desirable.

Accordingly, it is a general object of the present invention to provide a clothes washing machine of the type described that employs 20 compressed air as a fluid medium for the purpose of selectively controlling the movements of the diaphragm.

Another object of the invention is to provide in a clothes washing machine of the type noted, an arrangement including an air compressor and a storage tank operatively connected thereto and valve mechanism for selectively connecting the chamber disposed adjacent to the diaphragm to the storage tank and to the atmosphere, whereby compressed air may be stored in the tank during a washing or rinsing operation and then subsequently used in the chamber in order to effect movement of the diaphragm from its normal position into its operated position during a wash water or rinse water extracting operation.

A further object of the invention is to provide in a clothes washing machine of the type described, an improved and simplified washing 45 and wash water extracting and rinsing and rinse water extracting cycle.

Further features of the invention pertain to the particular arrangement of the elements of the clothes washing machine and to the elements of the electric circuit control network therefor, whereby the above-outlined and additional operating features thereof are attained.

The invention, both as to its organization and method of operation, together with further objects and advantages thereof, will best be

understood by reference to the following specification taken in connection with the accompanying drawings, in which Figure 1 is a plan view of a clothes washing machine embodying the present invention; Fig. 2 is a side elevational view of the machine shown in Fig. 1; Fig. 3 is a front elevational view of the machine shown in Figs. 1 and 2; Fig. 4 is an enlarged vertical sectional view of the machine, taken longitudinally of the tub in the direction of the arrows along the line 4—4 in Fig. 5; Fig. 5 is another enlarged vertical sectional view of the machine, taken transversely of the tub in the direction of the arrows along the line 5—5 in Fig. 4; Fig. 6 is a greatly enlarged plan view of a manually operable control dial that may be incorporated in the machine shown in Figs. 1 to 5, inclusive; Fig. 7 is an electrical diagram of a manual control system that may be incorporated in the machine shown in Figs. 1 to 5, inclusive; and Fig. 8 is an electrical diagram of a semi-automatic control system that may be incorporated in the machine shown in Figs. 1 to 5, inclusive.

Referring now to Figs. 1 to 5, inclusive, of the drawings, there is illustrated a clothes washing machine 10 of the general character of that disclosed in the previously mentioned Castner application and embodying the features of the present invention. The machine 10 comprises an upstanding base 11 carrying on the upper portion thereof an upstanding tub 12. The base 11 comprises front and rear walls 13 and 14, side walls 15 and 16 and a bottom wall 17. The bottom wall 17 has an enlarged centrally disposed opening 18 formed therein, and is provided adjacent to the corners thereof with downwardly depressed feet 19 adapted to engage a supporting floor, or the like. The top of the base 11 is open in order that the upper portion thereof may receive and enclose the lower portion of the tub 12 carried thereby as explained more fully hereinafter. The tub 12 comprises cooperating front and rear cup-shaped sections 20 and 21 secured together in facing liquid-tight relation by cooperating inner and outer rings or bands 22 and 23 secured together by a series of screws 24. The front section 20 comprises an upstanding front wall 25 and a connected rearwardly directed tubular side wall 26; while the rear section 21 comprises an upstanding rear wall 27 and a connected forwardly directed tubular side wall 28. The tubular side wall 26 comprises a laterally extending substantially flat forwardly and downwardly sloping top wall 29, two downwardly directed side walls 30 and 31 and an arcuate bottom wall 32; while the tubular side wall 28 comprises a laterally extending substantially flat horizontal top wall 33, two downwardly directed side walls 34 and 35 and an arcuate bottom wall 36. Accordingly, the rear edges or ends of the walls 29, 30, 31 and 32 of the front section 20 and the front edges or ends of the walls 33, 34, 35 and 36 of the rear section 21 are secured together in liquid-tight relation by the rings 22 and 23.

The bottom walls 32 and 36 respectively carry two laterally extending and longitudinally spaced-apart brackets 37 and 38 that may be secured thereto by welding, or the like, which brackets 37 and 38 are suitably secured to a longitudinally extending supporting plate 39 arranged below the tub 12. The opposite ends of the supporting plate 39 are carried upon two laterally extending substantially L-shaped members 40 and 41 re-

spectively secured to the front wall 13 and to the rear wall 14 by two series of screws 42 and 43. The members 40 and 41 are arranged within the base 11 and receive the opposite ends of the supporting plate 39 as noted above, whereby the supporting plate 39, as well as the tub 12, are supported in position within the upper portion of the base 11. Thus, the lower portion of the tub 12 is enclosed within the upper portion of the base 11 and cooperates with the bottom wall 17 to define a machinery compartment 44 in the lower portion of the base 11. The upper edges of the front and rear walls 13 and 14 are inwardly curved as indicated at 45 and 46 in order to engage the respective front and rear walls 25 and 27; and similarly the upper edges of the side walls 15 and 16 are inwardly curved and folded back upon themselves as indicated at 47 and 48 in order to engage the opposite sides of the bottom walls 32 and 36.

A substantially laterally extending rectangular opening 49 is formed substantially centrally in the top wall 29 of the front section 20 in order to render the interior of the tub 12 accessible from the exterior. The opening 49 is surrounded by an inwardly directed marginal throat 50 and is provided with a door 51 movable between open and closed positions with respect thereto. The door 51 includes inner and outer sheets 52 and 53 suitably secured together and mounted upon two laterally spaced-apart hinge mechanisms 54 of any suitable type. Also, the door 51 comprises latch mechanism indicated generally at 55 and comprising a rotatably mounted handle 56 that controls the sliding movements of two associated latch elements 57 that cooperate with the throat 50 in order securely to latch the door 51 in its closed position. It will be understood that the door 51 is normally latched in its closed position and that it is necessary first to rotate the handle 56 in order to release the latch mechanism 55 before the door 51 may be moved from its closed position into its open position. Subsequently, when the door 51 is moved from its open position back into its closed position the latch mechanism 55 operates automatically to latch the door 51 in its closed position.

Arranged within the tub 12 is an upstanding flexible substantially cup-shaped diaphragm 58 formed of rubber, or the like, and including what may be termed an end wall 59 and a flange wall 60, the marginal edge or perimeter of the flange wall 60 being clamped between the rings 22 and 23. The diaphragm 58 has a normal concave position in which it conforms substantially to the interior surface of the rear section 21 of the tub 12. In its concave position the diaphragm 58 cooperates with the front section 20 to define a compartment 61 within the tub 12, and cooperates with the rear section 21 to define a chamber 62 within the tub 12, the compartment 61 and the chamber 62 being separated from each other by the diaphragm 58. The compartment 61 is accessible from the exterior through the opening 49 when the door 51 occupies its open position and is adapted to receive cleansing liquid and clothes to be washed.

Also arranged within the compartment 61 adjacent to the rearwardly of the front wall 25 is an upstanding perforated wall or plate 63, the configuration of the plate 63 conforming substantially to that of the front wall 25. The plate 63 may be formed of one-piece die cast construction or pressed directly from a fairly heavy gauge of stainless steel, or the like, the plate 63 being

perforated by the provision of a number of holes 64 therein. Further, the position of the plate 63 spaced rearwardly with respect to the front wall 25 is maintained by a series of spaced-apart stanchions 65 disposed therebetween, the front ends of the stanchions 65 being suitably secured to the adjacent face of the front wall 25 and the rear ends of the stanchions 65 being suitably secured in aligned openings provided in the plate 63. Accordingly, the upstanding front wall 25 and the upstanding plate 63 define an upstanding space 66 therebetween, with which space 66 a downwardly extending drain conduit 67 provided in the bottom wall 32 communicates.

A forwardly directed substantially annular emboss 68 is formed in the upper central portion of the plate 63 in order to provide a substantially circular recess 69 surrounded thereby, the centers of the emboss 68 and of the recess 69 being substantially coincident with each other and with the arc of the bottom walls 32 and 36 of the respective sections 20 and 21 of the tub 12. A disk-like dasher plate 70 is arranged within the recess 69 and mounted upon the rear end of an operating shaft 71 that extends through aligned openings respectively formed in the front wall 25 and in the plate 63. More particularly, the operating shaft 71 is supported and journaled for rotation substantially along the longitudinal axis of the tub 12 in bearing structure including complementary sections 72 and 73 respectively disposed interiorly and exteriorly of the front wall 25 adjacent to the center of the emboss 68, whereby the sections 72 and 73 provide a liquid-tight joint surrounding the opening provided in the front wall 25 and preventing the escape from the tub 12 of wash liquid along the operating shaft 71. The front end of the operating shaft 71 carries a pulley 74 rigidly secured thereto, whereby the operating shaft 71 and the dasher plate 70 may be rotated unidirectionally.

As best shown in Fig. 5, the dasher plate 70 is rotated unidirectionally in the clockwise direction, as viewed from the front face thereof, and carries on its front face three relatively shallow outstanding vanes 75, 76 and 77, the vane 75 being disposed on one side of the center of rotation of the dasher plate 70 and the vanes 76 and 77 being disposed on the other side of the center of rotation of the dasher plate 70 and in radial spaced-apart relation with respect to each other. The vanes 75, 76 and 77 are removed from the center of rotation of the dasher plate 70 and extend in a crosswise to radial direction with respect to the center of rotation thereof, each of the vanes 75, 76 and 77 being tapered and provided with leading and trailing ends with respect to the direction of rotation of the dasher plate 70 so that the leading end of each vane is closer than the trailing end thereof to the front face of the dasher plate 70. For example, the leading ends of the vanes 75, 76 and 77 marked "L" may be in the plane of the front face of the dasher plate 70, while the trailing ends of the vanes marked "T" may be disposed outwardly therefrom, the taper being continuous between the ends "L" and "T." Also, a shallow recess 78 is provided in the front face of the dasher plate 70 between the vanes 76 and 77, this recess 78 assisting in the release of the clothes from the front face of the dasher plate 70 as explained more fully hereinafter. The central portion of the dasher plate 70 is provided with a forwardly directed boss 79 having a hole 80 therein that receives the rear end of the operating shaft 71.

as previously noted. Also a substantially annular resilient element 81 formed of rubber, or the like, is suitably secured upon the peripheral edge of the dasher plate 70 in order to prevent working of the clothes contained in the tub 12 between the dasher plate 70 and the plate 63 and the consequent breakage of buttons, or the like, carried upon the clothes.

Arranged within the upstanding space 66 between the front wall 25 and the plate 63 are an inlet conduit 82 and an overflow conduit 83. The upper open end of the overflow conduit 83 establishes the normal liquid level in the compartment 61 as indicated by the broken line 84, which level is disposed somewhat above the upper portion of the dasher plate 70. The lower end of the overflow conduit 83 projects through the bottom wall 32 into the machinery compartment 44 and is connected by a section of flexible hose 85 to a drain fixture 86. Also, a solenoid controlled valve 87 is arranged in the drain conduit 67, and the lower end of the drain conduit 67 is connected by a short section of flexible hose 88 to the drain fixture 86. The upper end of the inlet conduit 82 is curved outwardly toward the side wall 31 and terminates somewhat above the normal liquid level indicated by the broken line 84; while the lower end of the inlet conduit 82 projects through the bottom wall 32 the machinery compartment 44. An inlet valve mechanism 89 is arranged in the machinery compartment 44 and comprises a casing 90 including a hot water supply pipe 91, a cold water supply pipe 92 and an outlet pipe 93, the outlet pipe 93 being connected to the lower end of the inlet conduit 82. Further, the inlet valve mechanism 89 is solenoid controlled including a hot water solenoid 94 and a cold water solenoid 95. The pipes 91 and 92 project through a suitable opening, not shown, provided in the rear wall 14 and are suitably detachably connected respectively to a source of hot water and to a source of cold water in the laundry room. Of course, it will be appreciated that hot and cold valves, not shown, are arranged in the casing 90 of the inlet valve mechanism 89 that are respectively controlled by the hot water solenoid 94 and by the cold water solenoid 95.

Also arranged in the machinery compartment 44 is a drain pump 96 that is provided with a casing 97 having inlet and outlet connections 98 and 99. The inlet connection 98 is suitably connected by a short section of flexible hose 100 to the drain fixture 86, and the outlet connection 99 is suitably connected by a short section of flexible hose, not shown, to a drain pipe 101. The drain pipe 101 also extends through the opening, not shown, provided in the rear wall 14 and is suitably connected to drain plumbing, such, for example, as a laundry tray, in the laundry room.

In view of the foregoing description of the water supply and drain system that is incorporated in the machine 10, it will be understood that when the hot water solenoid 94 is energized alone, hot water is supplied from the hot water supply pipe 91 through the casing 90 of the inlet valve mechanism 89 into the inlet conduit 82 and is thus delivered into the compartment 61 provided in the tub 12; and, likewise, when the cold water solenoid 95 is energized alone, cold water is supplied from the cold water supply pipe 92 through the casing 90 of the inlet valve mechanism 89 into the inlet conduit 82 and is thus delivered into the compartment 61 provided in the tub 12. When both

of the solenoids 94 and 95 are energized warm water is supplied via the inlet conduit 82 into the compartment 61 as a result of the mixing of the hot water and the cold water in the casing 90 of the inlet valve mechanism 89. The valves controlled by the solenoids 94 and 95 are normally biased into their closed positions, and are, accordingly, operated into their closed positions when the respective solenoids 94 and 95 are de-energized. The water that is supplied into the compartment 61 accumulates therein until the head thereof rises to the normal level indicated by the broken line 84, whereupon any further water supplied into the compartment 61 overflows through the overflow conduit 83 and is delivered via the drain fixture 86 into the casing 97 of the drain pump 96; whereby, the overflowing water is pumped by the operating drain pump 96 through the drain pipe 101 to the exterior. The solenoid control valve 87 is normally biased into its closed position; however, when the solenoid 87 thereof is energized it is operated into its open position, whereby the water contained in the compartment 61 is drained through the drain conduit 67 into the drain fixture 86 and is thence pumped by the operating drain pump 96 through the drain pipe 101 to the exterior. Thus it will be understood that the overflow conduit 83 establishes the normal level of the water in the compartment 61 and both the water overflowed from the compartment 61 via the overflow conduit 83, and the water drained from the compartment 61 via the drain conduit 67 are pumped by the drain pump 96 through the drain pipe 101 to the exterior of the machine 10.

Also arranged within the machinery compartment 44 is an electric motor 102 of any suitable type that is preferably operative by a commercial source of 60 cycle 110 volts A. C. supply, the base of the motor 102 being suitably secured to the supporting plate 39. The motor 102 includes a rotor provided with an operating shaft, not shown, that projects from the opposite end bells thereof, the front and rear ends of the operating shaft respectively terminating in two solenoid-controlled clutch mechanisms 103 and 104, also suitably carried by the supporting plate 39. A stub shaft 105 is suitably journaled in a bearing hanger 106 that is also carried by the supporting plate 39, the rear end of the stub shaft 105 terminating in the clutch mechanism 103 and the front end of the stub shaft 105 having a pulley 107 rigidly secured thereto. The front end of the stub shaft 105 extends through an opening 108 formed in the front wall 13, whereby the pulley 107 is disposed forwardly of the front wall 13 and below and in alignment with the pulley 14. The pulleys 14 and 107 are of the V-belt type and are interconnected by a V-belt drive connection 109. The pulleys 14 and 107 and the V-belt 109 are enclosed in a hood 110 removably secured to the front walls 25 and 13 by an arrangement including a plurality of screws 111. The screws 111 extend through openings provided in the hood 110, the inner ends of the screws 111 being threaded into tapped holes provided in certain of the stanchions 65.

Also, two aligned stub shafts 112 and 113 are arranged within the machinery compartment 44, the front end of the stub shaft 112 terminating in the clutch mechanism 104 and the rear end of the stub shaft 112 being suitably journaled in a bearing hanger 114 that is carried by the supporting plate 39. The adjacent ends of the stub shafts 112 and 113 are operatively connected to the com-

ponent elements of a fluid drive or coupling unit 115. For example, the rear end of the stub shaft 112 may be connected to the bladed element of the unit 115 and the front end of the stub shaft 5 113 may be connected to the casing, indicated at 116, of the unit 115, the casing 116 containing a suitable quantity of hydraulic medium, such, for example, as oil. Further, an air compressor 117 is arranged within the machinery compartment 14 and carried by the supporting plate 39, the air compressor 117 being provided with a rotor having an operating shaft 118, the front end of the operating shaft 118 being connected to the adjacent rear end of the stub shaft 113 by a coupling element 119. The rotor, not shown, of the drain pump 96 directly surrounds and is rigidly secured to the operating shaft, not shown, of the motor 102, whereby the drain pump 96 is operated any time operation of the motor 102 is initiated.

Arranged within the lower portion of the machinery compartment 44 are two laterally spaced-apart substantially cylindrical storage tanks 120 and 121 connected together by a pipe 122. The air compressor 117 may be of any suitable type 25 and comprises a casing 123 having inlet ports, not shown, communicating with the atmosphere, and discharge ports that are connected by a conduit 124 to the tank 120, a check valve 125 being included in the conduit 124. A conduit 126 is 30 connected to the tank 121 and extends to a solenoid controlled inlet valve 127 that is also connected to a conduit 128. The inlet valve 127 is normally biased into its closed position and is provided with an operating solenoid 127'; while 35 the conduit 128 is connected by a fixture 129 secured within a depression 130 formed in the lower portion of the bottom wall 36 to the chamber 62. Also, the conduit 128 is connected to a solenoid controlled exhaust valve 131, that, in 40 turn, is connected to an exhaust conduit 132 communicating with the atmosphere. The valve 131 is normally biased into its closed position and is provided with an operating solenoid 131'. Further, an adjustable relief or safety valve 133 45 is connected to the conduit 128 and to a conduit 134 that communicates with the atmosphere. It will be understood that the relief valve 133 is adjustable in order to permit the establishment of a predetermined pressure within the conduit 128, whereby the relief valve 133 is selectively operated to its open and closed positions in response to pressures of the air in the conduit 128 respectively above and below the predetermined pressure mentioned. Further, a pressure responsive safety switch, generally indicated at 135, 50 communicates with the conduit 128, the switch 135 being adjustable and including contact structure selectively operative between closed and open positions in response to a gauge pressure in the conduit 128. Finally, a pressure responsive snap acting switch, generally indicated at 136, 55 communicates with the tank 120, the switch 136 being adjustable and including contact structure that is selectively operative with a snap action between closed and open positions in response to a predetermined pressure in the tank 120.

Finally, the machine 10 comprises a program selector switch 137 and a push button switch 138, both arranged within the machinery compartment 44, the switch 137 being mounted on the right-hand side of the front wall 13 and the switch 138 being mounted on the left-hand side of the front wall 13. The program selector switch 137 is of the manually operable type including a rotatably mounted operating shaft 139

projecting through an opening provided in the front wall 13 and carrying a control dial 140. The push button switch 138 is of the manually operable type and includes a push button 141 projecting through an opening provided in the front wall 13 and operable from the exterior of the machine 10. As best shown in Fig. 6, the control dial 140 comprises a substantially centrally disposed knob portion 142 and an outwardly flared skirt 143 carrying indicia that cooperates with an index pointer 144 mounted adjacent thereto upon the outer surface of the front wall 13.

In the machine 10 the base 11 may be formed of sheet steel and of wrap-around construction; and likewise the hood 110 may be formed of sheet steel and of die-pressed construction. Preferably, the sections 20 and 21 of the tub 12, as well as the component elements of the door 51, are formed of corrosion resistant material, such, for example, as stainless steel. Finally, the base 11 and the hood 91 may be provided with an exterior finish of white enamel, or the like. The machine 10 is readily portable, and as a constructional example the tub 12 may have substantially the following dimensions. The distance between the rear wall 27 and the center of the ring 22 may be 7 inches; the distance between the center of the ring 22 and the front wall 25 may be 8 inches; and the plate 63 may be spaced 1 inch rearwardly of the front wall 25. The arc of the bottom walls 32 and 36 may be on a 9" radius, whereby the side walls 30-31 and 34-35 are spaced from each other 18 inches. Further, the side walls 34 and 35 may extend upwardly 11 inches above the center line of the operating shaft 71 to join the horizontal top wall 33; while the side walls 30 and 31 extend upwardly suitably above the center line of the operating shaft 71 to join the forwardly sloping top wall 29. Finally, the front portion of the top wall 29 may be disposed 1½ inches below the rear portion thereof to provide the forward slope noted.

For the purpose of controlling the operation of the washing machine 10 an electric circuit network is incorporated therein, which circuit network may be either of the manually governed type, as illustrated in Fig. 7, or of the semi-automatically governed type, as illustrated in Fig. 8.

Considering the manually governed circuit network illustrated in Fig. 7, the program selector switch 137 is provided with seven insulating control cams C1 to C7, inclusive, rigidly secured to the operating shaft 139 thereof and respectively cooperating with seven control switches S1 to S7, inclusive. Also, the operating shaft 139 of the program selector switch 137 is capable of limited longitudinal movement and cooperates with a master switch MS, whereby the master switch MS is operated into its open position by an insulator 145 carried by the inner end of the operating shaft 139 when the control dial 140 is pressed inwardly, the master switch MS being operated into its closed position when the control dial 140 is moved outwardly, the inward and outward movements of the control dial 140 being longitudinally of the operating shaft 139 and with respect to the front wall 13.

As illustrated in Fig. 7, the hot water solenoid 94 and the cold water solenoid 95 of the inlet valve mechanism 89 are indicated; the solenoids 131' and 127' of the air valves 131 and 127 are indicated; the solenoid 87' of the drain valve 87 is indicated; and the solenoids 103' and 104' of the clutch mechanisms 103 and 104 are indicated.

Further, the pressure responsive switch 135 is indicated; and the snap acting pressure responsive switch 136 is indicated. Finally, the program selector switch 137, the push button switch 138 and the motor 102 are indicated. Further, the circuit control network comprises a source of 60 cycle 110 volts A. C. the terminals of which are indicated at "+" and "-", the "-" terminal being connected to a supply conductor 150 grounded in the machine 10, the "+" terminal being connected to a supply conductor 151 ungrounded in the machine 10. One terminal of the master switch MS is connected to the supply conductor 151 and the other terminal thereof is connected to a supply conductor 152. One terminal of each of the solenoids 94, 95, 131', 127', 87', 103' and 104', as well as one terminal of the motor 102, is connected to the supply conductor 150. The control switch S1 comprises two springs, one of which is connected to the supply conductor 152, and the other of which is connected to the other terminal of the solenoid 94. The control switch S2 comprises two springs, one of which is connected to the supply conductor 152, and the other of which is connected to the other terminal of the solenoid 95. The control switch S3 comprises two springs, one of which is connected to the supply conductor 152, and the other of which is connected to the other terminal of the solenoid 131'. The control switch S4 comprises two springs, one of which is connected to the supply conductor 152, and the other of which is connected to the other terminal of the solenoid 127'. The control switch S5 comprises two springs, one of which is connected to the supply conductor 152, and the other of which is connected to the other terminal of the solenoid 87'. The control switch S6 comprises two springs, one of which is connected to the supply conductor 152, and the other of which is connected to one terminal of the switch 135, the other terminal of the switch 135 being connected to the other terminal of the solenoid 103'. The control switch S7 comprises four springs, the first or lowermost of which is connected commonly to one terminal of the switch 136 and to one terminal of the motor 102, the other terminal of the switch 136 being connected to the other terminal of the solenoid 104'. The second and third springs of the control switch S7 are respectively connected to the supply conductors 152 and 151, while the fourth spring thereof is connected to a control conductor 154. The push button switch 138 comprises two bridging members 155 and 156 respectively controlling pairs of contacts. One of the contacts controlled by the bridging member 155 is connected to the control conductor 154, and the other contact of this pair is connected to the other terminal of the solenoid 127'; while one of the contacts controlled by the bridging member 156 is connected to the control conductor 154, and the other contact of this pair is connected to the other terminal of the solenoid 131'.

Considering now the operation of the machine 10 in conjunction with the manually governed circuit control network, illustrated in Fig. 7, when the control dial 140 occupies its normal "off" position, the control cams C1 to C6, inclusive, operate the respectively associated control switches S1 to S6, inclusive, into their open positions, while the control cam C7 operates the control switch S7 so that the contacts between the first and second springs thereof are opened and the contacts between the third and fourth springs thereof are closed. Also, at this time

when the control dial 140 occupies its normal inward position the master switch MS is operated to its open position. Further, at this time the push button switch 138 is normally biased to open the bridging members 155 and 156 with respect to the associated pairs of contacts. Accordingly, all of the electric circuits are open at this time.

In order to wash a given load of clothes, the operator first rotates the handle 56 in order to unlatch the door 51, whereupon the door 51 is moved to its open position. The clothes are then placed within the compartment 61 through the opening 49 and hot or warm or cold water is admitted into the compartment 61 as required by the character of the fabrics to be washed. Then an appropriate amount of detergent is placed in the wash water contained in the compartment 61, and the door 51 is returned to its closed position, whereby it is automatically latched securely in place by the latch mechanism 55.

In order to admit hot water into the compartment 61, the user first rotates the control dial 140 into its "hot fill" position, the 40° position thereof with respect to the normal "off" position thereof, and then moves the control dial 140 outwardly. When the control dial 140 is rotated into its "hot fill" position, the control cam C2 operates the control switch S2 to its closed position in order to preselect the circuit of the hot water solenoid 95; the control cam C3 operates the control switch S3 to its closed position in order to preselect the circuit of the solenoid 131'; and the control cam C7 operates the control switch S7 to open the contacts between the third and fourth springs thereof and to close the contacts between the first and second springs thereof. When the contacts between the third and fourth springs of the control switch S7 are thus opened, the push button switch 138 is disabled for a purpose more fully explained hereinafter; and when the contacts between the first and second springs of the control switch S7 are thus closed, the circuits of the motor 102 and the solenoid 104' are preselected. When the control dial 140 is then moved outwardly, the master switch MS is closed connecting the supply conductor 151 to the supply conductor 152 in order to complete the previously selected circuits. Specifically, the circuit for operating the motor 102 is completed in order to initiate operation thereof; and the circuit for energizing the solenoid 104' is completed, assuming that less than a predetermined pressure of the compressed air in the storage tanks 120 and 121 maintains at this time so that the pressure responsive switch 136 occupies its closed position. Accordingly, the solenoid 104' is energized, whereby the clutch mechanism 104 is operated into its clutched position, the operating shaft of the motor 102 rotating the stub shaft 112 through the clutch mechanism 104. The rotating stub shaft 112 drives the stub shaft 113 through the fluid coupling unit 115, whereby the operating shaft 118 of the air compressor 117 is rotated causing the air compressor 117 to take in air from the atmosphere and to compress it in the casing 123 and then to discharge it through the conduit 124 and the check valve 125 into the connected storage tanks 120 and 121. The check valve 125 prevents the compressed air contained in the storage tanks 120 and 121 from leaking back through the conduit 124 into the casing 123 of the air compressor 117 after operation of the air compressor 117 is subsequently arrested, in a well-known manner.

Accordingly, as time proceeds the pressure of the compressed air in the storage tanks 120 and 121 is increased due to operation of the air compressor 117, until a predetermined pressure of the air therein is reached, depending upon the setting of the pressure responsive of the snap switch 136. For reference purposes, it may be assumed that the pressure responsive switch 136 is set to operate at a pressure of three atmospheres gauge of the air in the storage tanks 120 and 121. Hence, when the pressure of the air in the storage tanks 120 and 121 is below three atmospheres gauge, the snap switch 136 occupies its closed position; and when a pressure of the air in the storage tanks 120 and 121 of three atmospheres gauge is reached, the switch 136 is snapped to its open position interrupting the circuit for energizing the solenoid 104' so that the clutch mechanism 104 is returned to its de-clutched position. Thereafter, in the event the pressure of the air in the storage tanks 120 and 121 falls below the three atmospheres gauge, the switch 136 is returned with a snap action into its closed position in order again to complete the circuit for energizing the solenoid 104' so as again to operate the clutch mechanism 104 to its clutched position. Thus, it will be understood that the pressure responsive switch 136 comprises an adjustable pressure regulator maintaining the pressure of the air in the storage tanks 120 and 121 at the three atmospheres gauge so long as the motor 102 is operating. Moreover, it will be understood that the fluid drive unit 115 accommodates slippage between the operating shaft of the motor 102 and the stub shaft 113, and consequently the operating shaft 118 of the compressor 117, whereby the fluid drive unit 115 also acts as a regulator to prevent the presence of an exceedingly high pressure of the air in the storage tanks 120 and 121 should the pressure responsive switch 136 be inadvertently set or adjusted to an inordinate and unreasonably high pressure.

Also, at this time the solenoid 95 of the inlet valve mechanism 89 is energized, whereby hot water is supplied from the hot water supply pipe 91 via the casing 90 of the inlet valve mechanism 89 and the inlet conduit 82 to the compartment 61. Further, the winding of the solenoid 131' is energized in order to insure that the exhaust valve 131 occupies its open position venting the chamber 62 behind the diaphragm 58 via the conduits 128 and 132 to the atmosphere. This arrangement insures that the incoming water supplied to the compartment 61 returns the diaphragm 58 completely into its concave position at this time. Moreover, since the motor 102 is operating, the rotor of the drain pump 96 is rotated so that any water accumulating in the drain fixture 86 is pumped via the casing 97 of the drain pump 96 and the drain pipe 101 to the exterior of the machine 10. Accordingly, at this time should the user inadvertently fill the compartment 61 to overflowing, the excess water therein falls through the overflow conduit 83 into the drain fixture 86 and is pumped by the drain pump 96 via the drain pipe 101 to the exterior. This arrangement positively prevents overflowing of the machine 10 and the consequent flooding of the laundry room in which it is located.

After the user has filled the compartment 61 with a charge of wash water, she operates the control dial 140 into its inward position in order to operate the master switch MS to its open position so as to interrupt the previously selected

circuits. At this time operation of the motor 102 is arrested; the solenoid 104' is de-energized to effect operation of the clutch mechanism 104 to its declutched position; the solenoid 131' is de-energized to effect operation of the exhaust valve 131 to its closed position; and the hot water solenoid 95 is de-energized to effect operation of the inlet valve mechanism 89 to its closed position.

In view of the foregoing description of the control of the circuit network incident to filling of the compartment 61 with hot water, it will be understood that the operation thereof is substantially identical incident to filling of the tub with warm water or cool water. Specifically, when the control dial 140 is rotated to its "warm fill" position, the 80° position thereof, the circuits of both of the solenoids 94 and 95 are preselected; and when the control dial 140 is rotated to its "cold fill" position, the 120° position thereof, the circuit of only the cold water solenoid 94 is preselected. In either case the preselected circuits are completed when the control dial 140 is ultimately operated into its outward position.

After the compartment 61 has been filled with hot or warm or cold water in the manner previously explained, the control dial 140 is rotated into its "wash" position, the 160° position thereof, and is then operated into its outward position. When the control dial 140 is rotated into its "wash" position, the control cam C3 operates the control switch S3 to preselect the circuit of the solenoid 131'; the control cam C6 operates the control S6 to preselect the circuit of the solenoid 103'; and the control cam C7 operates the control S7 to preselect the circuit of the motor 102 and the circuit of the solenoid 104'. At this time when the control dial 140 is operated into its outward position the motor 102 is operated, and the clutch 104 is operated under the control of the pressure responsive switch 136. Also, the exhaust valve 131 is operated to its open position, and the solenoid 103' is energized effecting operation of the clutch mechanism 103 into its clutched position. Accordingly, the motor 102 effects rotation of the stub shaft 105 and the consequent rotation of the pulley 107, whereby the pulley 74 is rotated through the V-belt 109 effecting rotation of the operating shaft 71 and the dasher plate 70 in the compartment 61. As previously explained, the dasher plate 70 is rotated in the counterclockwise direction, as viewed from the front of the machine 10, the clockwise direction as viewed from the face thereof; whereby, the dasher plate 70 moves and rearranges the clothes contained in the compartment 61 formed in the tub 12 in a substantially circular upstanding path. Specifically, the dasher plate 70 lightly grasps the clothes as it is rotated unidirectionally in the clockwise direction, as viewed in Fig. 5, by an angular shearing contact therewith and then quickly discharges the clothes in order that they are moyed and rearranged in the substantially circular upstanding path, as previously noted. This angular shearing contact with which the clothes are lightly grasped is effected largely by the disposition of the shallow tapered vanes 75, 76 and 77 provided upon the front face of the dasher plate 70; while this quick discharge of the clothes from the front face of the dasher plate 70 is materially facilitated by the shallow recess 78 disposed in the front face thereof and positioned between the vanes 76 and 77.

After the clothes have been washed by the machine 10 for an appropriate time interval, the user returns the control dial 140 into its inward

position operating the master switch MS into its open position in order to effect opening of all of the electric circuits as previously explained. At this time the user may open the door 51 and examine the clothes in order to determine that they are washed to satisfaction, again returning the door 51 to its closed position after the examination. In order to effect further washing of the clothes in the compartment 61, it is only necessary for the user again to return the control dial 140 to its outward position. On the other hand, assuming that the clothes are washed to the satisfaction of the user, the control dial 140 is rotated into its "drain" position, the 200° position thereof, and then operated into its outward position.

When the control dial 140 is rotated into its "drain" position the control cam C5 operates the control switch S5 to preselect the circuit of the solenoid 87'; and the control cam C7 operates the control switch S7 to preselect the circuit of the motor 102 and the circuit of the solenoid 104'. When the control dial 140 is then operated into its outward position, the preselected circuits mentioned are completed. Specifically, the solenoid 87' is energized effecting operation of the drain valve 87 into its open position so that the wash water in the compartment 61 is drained via the drain conduit 67 into the drain fixture 86, and is then pumped by the operating drain pump 96 to the exterior, since the motor 102 is operating at this time. Ordinarily, by this time the pressure responsive switch 136 has been operated to its open position as a consequence of the presence of the pressure of three atmospheres gauge of the air in the storage tanks 120 and 121; however, at this time the circuit of the solenoid 104' is otherwise preselected and is completed in the event the pressure responsive switch 136 should happen to occupy its closed position. However, for the purpose of explanation, it may be assumed that during the filling and washing steps, the operation of the air compressor 111 is effective to store air at three atmospheres gauge in the storage tanks 120 and 121 effecting operation of the switch 136 to its open position.

After the user has given the machine 10 sufficient time to drain the wash water from the compartment 61, the control dial 140 is returned to its inward position and then rotated into its "squeeze" position, the 240° position thereof, and then returned to its outward position.

When the control dial 140 is rotated into its "squeeze" position, the control cam C4 operates the switch S4 to preselect the circuit of the solenoid 127'; the control cam C5 operates the control switch S5 to preselect the circuit of the solenoid 87'; and the control cam C7 operates the control switch S7 to preselect the circuit of the operating motor 102 and the circuit of the solenoid 104'. When the control dial 140 is then operated into its outward position, the master switch MS is closed completing the preselected circuits noted, the completion of the circuit of the solenoid 104' being under the direct control of the pressure responsive switch 136, as previously noted. Specifically, the inlet valve 127 is operated into its open position while the exhaust valve 131 occupies its closed position. Accordingly, the compressed air in the storage tanks 120 and 121 is admitted into the conduit 128 and consequently into the chamber 62 in order to move the diaphragm 58 from its normal concave position into its operated convex position; whereby, the diaphragm 58 exerts a squeezing action upon

the clothes in the compartment 61, the clothes being squeezed between the diaphragm 58 and the plate 63 and the dasher plate 70. The absorbed wash water in the clothes is expressed therefrom into the space 66 and falls through the drain conduit 67 and is pumped to the exterior by the drain pump 96, the drain valve 87 occupying its open position and the motor 102 being operated at this time. During the time that the diaphragm 58 is exerting a squeezing action upon the clothes in the compartment 61, the door 51 is retained in its closed position, the door 51 being retained in its closed position by the latch mechanism 55.

When the inlet valve 127 is thus operated into its open position, the pressure in the system, including the storage tanks 120 and 121 and the chamber 62, with the diaphragm 58 in its operated convex position, quickly equalizes; whereby it is not ordinarily necessary to retain the control dial 140 in its "squeeze" position for a great length of time; however, should the control dial 140 be retained in its "squeeze" position a considerable length of time, there would be a tendency for the operating compressor 117 further to increase the pressure in the system, including the storage tanks 120 and 121 and the chamber 62 behind the diaphragm 58 in its operated convex position. In order to prevent this pressure in the system from rising to an inordinate and undesirably high pressure the safety valve 133 may be adjusted to a pressure of approximately 1½ atmospheres gauge. Accordingly, the operation of the compressor 117 at this time is ineffective to increase the pressure in the system above the pressure of 1½ atmospheres gauge, since the safety valve 133 acts as a poppet or relief valve passing the excess air to the atmosphere. Of course, it will be understood that when the inlet valve 127 is operated to its open position that the pressure in the storage tanks 120 and 121 immediately falls causing the pressure responsive switch 136 to be operated to its closed position energizing the solenoid 104' to effect operation of the clutch mechanism 104 into its clutched position and the consequent operation of the compressor 117 from the operating motor 102.

Also it is noted that when a positive gauge pressure is present in the conduit 128, the pressure responsive switch 135 is operated into its open position in order to interrupt a further point in the circuit of the solenoid 103' so as positively to prevent operation of the clutch mechanism 103 into its clutched position when there is a positive pressure in the conduit 128 and consequently in the chamber 62. This arrangement positively prevents operation of the dasher plate 70 while the diaphragm 58 occupies its operated convex position effecting squeezing of the clothes against the dasher plate 70. This arrangement is very advantageous as it positively prevents inadvertent operation of the dasher plate 70 while the clothes in the compartment 61 are undergoing the squeezing action, as operation of the dasher plate 70 at this time would damage the clothes.

Accordingly, after the control dial 140 has been operated into its "squeeze" position and then operated into its outward position for a short time interval, it may be returned to its inward position in order to cause operation of the master switch MS into its open position. The control dial 140 is then rotated into its "hold" position, the 230° position thereof, and is then operated into its outward position. At this time the control cam C5 effects operation of the control switch

S5 so that the circuit of the solenoid 87' is preselected; and the control cam C7 effects operation of the control switch S7 so that the circuit of the motor 102 and the circuit of the solenoid 104' are preselected. Thus the drain valve 87 occupies its open position so that the water expressed from the clothes in the compartment 61 is drained into the drain conduit 67 and pumped by the operating drain pump 96 to the exterior. Also, the motor 102 is operated, and the clutch mechanism 104 is operated to its closed position in order to effect operation of the air compressor 117 so that the operation of the air compressor 117 is again placed under control of the pressure responsive switch 136 in the manner previously explained. At this time when the control dial 140 occupies its "hold" position the inlet valve 127 occupies its closed position and the exhaust valve 131 occupies its closed position, whereby the communication between the storage tanks 120 and 121 and the chamber 62 is cut off by the inlet valve 127, and the communication between the chamber 62 and the atmosphere is cut off by the exhaust valve 131. Accordingly, the air compressor 117 may proceed with its operation to raise the pressure of the compressed air in the storage tanks 120 and 121 back toward the three atmospheres gauge previously noted; and the air in the chamber is trapped therein at the 1½ atmospheres gauge previously noted so as to hold the diaphragm 58 in its operated convex position in order to hold the squeezing action upon the clothes in the compartment 61. This hold operation of the machine 10 requires no supervision by the user and may proceed for a suitable time interval, normally four minutes being sufficient.

At the conclusion of the hold operation, the control dial 140 is returned to its inward position and then rotated into its "release" position, the 320° position thereof, and then returned to its outward position. When the control dial 140 is rotated into its "release" position, the control cam C3 operates the control switch S3 to preselect the circuit of the solenoid 131'; the control cam C5 operates the control switch S5 to preselect the circuit of the solenoid 87'; and the control cam C7 operates the control switch S7 to preselect the circuit of the motor 102 and the circuit of the solenoid 104'. When the control dial 140 is operated to its outward position, the preselected circuits mentioned are completed, whereby the motor 102 operates effecting operation of the air compressor 117 since the clutch mechanism 104 is operated into its clutched position. The drain valve 87 is operated into its open position in order that any residual wash water in the compartment 61 may be pumped by the operating drain pump 96 to the exterior; and the exhaust valve 131 is operated to its open position in order to exhaust to the atmosphere the compressed air in the chamber 62 so that the diaphragm 58 may collapse from its operated convex position back into its normal concave position due to the weight of the clothes in the compartment 61. Of course, when the exhaust valve 131 is thus opened the pressure in the compartment 62 is relieved to atmospheric pressure; whereby, the pressure in the conduit 128 again falls to zero atmospheres gauge pressure causing the pressure responsive switch 135 to be returned into its closed position so as again to condition the circuit of the solenoid 103' of the clutch mechanism 103. At this time the control dial 140 is returned to its inward position,

and then rotated into its "off" position, the 360° or 0° position thereof.

When the control dial 140 is thus returned to its "off" position the control cam C7 operates the switch S7 in order to open the contacts between the first and second springs thereof and to close the contacts between the third and fourth springs thereof. This operation of the control switch S7 prepares the circuit extending to the push button switch 138. Thus when the control dial 140 occupies its "off" position, the circuits extending to the push button switch 138 are prepared. Accordingly, in the event the push button switch 138 is operated at this time, circuits are completed for energizing the solenoids 127' and 131', whereby the inlet valve 127 and the exhaust valve 131 are operated to their open positions. This arrangement effects the complete release of pressure in the system, including the storage tanks 120 and 121, the conduit 128 and the compartment 62 disposed behind the diaphragm 58. While it is not necessary to release the pressure of the compressed air stored in the tanks 120 and 121 after operation of the machine 10, this may be accomplished if desired as a result of momentary operation of the push button 138 when the control dial 140 occupies its "off" position, as explained above. The arrangement does permit the complete reduction of pressure in the storage tanks 120 and 121 and is, of course, useful when it is desired to make necessary adjustment or repairs of the machine 10 involving the storage tanks 120 and 121.

Continuing now with the operation of the machine 10, it will be understood that after a wash operation has been performed and the wash water has been squeezed from the clothes, all as explained above, the user of the machine may effect an appropriate rinsing operation. Specifically, the user may rotate the control dial 140 sequentially into its "warm fill" position, thereafter into its "wash" position, and then into its "drain" position, its "squeeze" position, its "hold" position, its "release" position, and ultimately back into its "off" position in order to cause the machine 10 to be operated in a manner substantially identical to that previously described so as to carry out the warm water rinsing operation upon the clothes in the compartment 61 in the tub 12. After the user has operated the machine 10 to carry out a warm water rinsing operation, as immediately described above, she may repeat the manipulations explained in order to cause the machine 10 to carry out a subsequent cold water rinsing operation. The over-all operation of the machine to carry out a washing operation followed by a warm water rinsing operation and then by a cold water rinsing operation is very advantageous as it positively insures that all detergent is removed from the clothes undergoing the over-all washing operation. Moreover, the warm water rinsing operation and the cold water rinsing operation may be carried out in such manner that overflowing of the compartment 61 is effected, as an overflowing rinsing operation is particularly useful in effecting the removal of any scum or curds from the compartment 61. Of course, at the conclusion of the cold water rinsing operation, the diaphragm 58 is operated so as to express the cold rinse water from the clothes contained in the compartment 61. Accordingly, after completion of the cold water rinsing operation and the release of the diaphragm 58, the door 51 may be

opened and the clothes may be removed from the compartment 61 and transferred to a drying machine in order to prepare the clothes for ironing.

Reconsidering the operation of the machine 10, it will be appreciated that utilization may be made of the gas law: $P_1V_1=P_2V_2$ so that when the inlet valve 127 is operated into its open position the required pressure is automatically established in the system including the storage tanks 120 and 121 and the chamber 62 behind the diaphragm 58 so as to force the diaphragm 58 toward the plate 63 and the dasher plate 70 in order to bring about immediately the desired squeezing pressure upon the clothes in the compartment 61. For example, in the event the combined volume of the storage tanks 120 and 121 is substantially equal to the volume of the chamber 62 when the diaphragm 58 occupies its operated convex position, it will be appreciated that upon equalization of the pressure in the system a pressure of two atmospheres absolute is automatically obtained in the event of an initial pressure of four atmospheres absolute in the storage tanks 120 and 121. Recapitulating, an initial pressure of three atmospheres gauge in the storage tanks 120 and 121 will obtain a final pressure of one atmosphere gauge in the system upon operation of the inlet valve 127 into its open position under the conditions noted. As a matter of construction and arrangement, it is preferred that an ultimate pressure of about 1½ atmospheres gauge is obtained in the chamber 62 immediately upon opening of the inlet valve 127 and that the initial pressure in the storage tanks 120 and 121 is approximately three atmospheres gauge, whereby it may be calculated that the combined volume of the storage tanks 120 and 121 should be approximately 1.67 times the volume of the chamber 62 when the diaphragm 58 occupies its operated convex position under the conditions explained.

Of course, it will be appreciated that in the event the desired initial pressure is not maintained in the storage tanks 120 and 121 the resulting pressure in the system will be somewhat below that desired immediately when the valve 127 is operated to its open position; however, the pressure in the system continues to rise by virtue of continued operation of the compressor 117 and until the desired pressure in the system is obtained by virtue of the setting of the adjustable safety valve 133.

Now considering the semi-automatically governed circuit network illustrated in Fig. 8, the program selector switch 237 is provided with eight insulating control cams C1 to C8, inclusive, rigidly secured to the operating shaft 239 thereof, that respectively cooperate with eight control switches S1 to S8, inclusive. Also, the operating shaft 239 of the program selector switch 237 is capable of limited longitudinal movement and cooperates with a master switch MS, whereby the master switch MS is operated into its open position by an insulator 245 carried by the inner end of the operating shaft 239 when the control dial 240 is pressed inwardly, the master switch MS being operated into its closed position when the control dial 240 is moved outwardly, the inward and outward movements of the control dial 240 being longitudinal of the operating shaft 239 and with respect to the front wall 13.

As illustrated in Fig. 8, the modified form of the program selector switch 237 further comprises a timer motor 250, speed reduction gearing 251 and an overrunning friction clutch 252 operatively

connected to the operating shaft 239 thereof. Specifically, the timer motor 250 is of the synchronous type provided with a rotor having an operating shaft, not shown, connected to the speed reduction gearing 251; and the speed reduction gearing 251 is operatively connected to one of the clutch plates of the overrunning clutch 252, the other clutch plate of the overrunning clutch 252 being connected to the extreme inner end of the operating shaft 239. The overrunning clutch 252 permits rotation of the operating shaft 239 by the manual control dial 240 independently of the timer motor 250. On the other hand, operation of the timer motor 250 effects rotation of the operating shaft 239 at a controlled and timed rate through the speed reduction gearing 251 and the overrunning clutch 252 in an obvious manner.

The general connection and arrangement of the master switch MS and the control switches S1 to S7, inclusive, in the program selector switch 237 are the same as those in the program selector switch 137 previously described in conjunction with Fig. 7. However, in the program selector switch 237 the additional control switch S8 that is operated by the additional control cam C8 is arranged to govern the additional timer motor 250 that is incorporated in the program selector switch 237. Specifically, the control switch S8 comprises two springs, one of which is connected to the supply conductor 152, and the other of which is connected to one terminal of the timer motor 250, the other terminal of the timer motor 250 being connected to the supply conductor 150.

The general operation of the semi-automatic control network disclosed in Fig. 8 is fundamentally the same as the manual control network disclosed in Fig. 7, except that the rotation of the operating shaft 139 thereof from the first "control" position thereof, the 72° position thereof, back into the "off" position thereof, the 360° or 0° position thereof, is carried out automatically by the timer motor 250 under the control of the control switch S8 governed by the control cam C8.

Specifically, the filling of the compartment 61 with hot water or warm water or cold water is governed manually in the same manner as that previously described in conjunction with the circuit control network disclosed in Fig. 7. In Fig. 8, the hot fill position, the warm fill position, and the cold fill position of the program selector switch 137 are respectively illustrated at the 24°, 40° and 56° positions thereof; while the first "control" position of the program selector switch 237 is illustrated at the 72° position thereof. Accordingly, when the control dial 240 is rotated into its first "control" position, the 72° position thereof, the control cam C8 operates the control switch S8 to its closed position in order to preselect the circuit of the timer motor 250. Further, the control cam C6 operates the control switch S6 to preselect the circuit of the solenoid 103 as previously explained. At this time when the control dial 240 is moved to its outward position, the preselected circuits mentioned are closed by virtue of the operation of the master switch MS into its closed position. Accordingly, the timer motor 250, upon operating, rotates the operating shaft 239 at the predetermined timed rate further in the clockwise direction from its first "control" position back into its "off" position. When the operating shaft 239 of the program selector switch 237 is thus returned back into its "off" position,

the control cam C8 operates the control switch S8 into its open position interrupting the circuit for the timer motor 250 in order to arrest further operation of the program selector switch 237. Also, at this time the other control cams C1 to C7, inclusive, selectively operate the respectively associated control switches S1 to S7, inclusive, in order to interrupt all of the electric circuits and to return the circuit network into its normal or "off" position, in a manner substantially identical to that explained in conjunction with the circuit control network illustrated in Fig. 7.

In view of the foregoing, it will be understood that when automatic operation of the program selector switch 237 is initiated in its first "control" position, the 72° position thereof, that it is operated continuously and automatically back into its "off" position, the 360° or 0° position thereof, during a predetermined time interval by the timer motor 250, whereby the control cams C1 to C7, inclusive, selectively operate the respectively associated control switches S1 to S7, inclusive, in order to bring about an automatic timed cycle of the machine 10.

It will be observed that the first "control" or wash position of the control dial 240 of the program selector switch 237 extends from the 72° position thereof to the 152° position thereof, covering an arc of 80° and a corresponding time interval of ten minutes, since the rate of operation of the timer motor 250 corresponds to 8° of rotation per minute of the operating shaft 239. Accordingly, incident to rotation of the control dial 240 into its first "control" position, it may be selectively set in any position thereof between the 72° position thereof and the 152° position thereof, thereby preselecting an adjustable time interval for the wash cycle within the ten minutes range. For example, initial rotation of the control dial 240 into the 72° and 80° positions thereof respectively correspond to washing times of ten minutes and nine minutes. Thus when the user operates the control dial 240 into its first "control" position, she also sets the desired washing time within the ten minutes range as noted above prior to operation of the control dial 240 into its outward position.

As illustrated in Fig. 8, the washing cycle comprising a wash step of a maximum time duration of ten minutes, a following drain step of four minutes, wherein the initial wash water is drained from the compartment 61, followed by a squeeze step of one minute. Thereafter, the diaphragm 58 is retained in its operated convex position during a hold step of four minutes; thereafter a release step of ½ minute is effected in order to insure that the diaphragm 58 is released from its operated convex position and returned back to its normal concave position. At this time a warm fill step is carried out for three minutes, during which time the compartment 61 is filled with warm water, some overflowing of the compartment 61 being obtained in the three minutes time interval. At the conclusion of the warm fill step, an agitation step of two minutes is effected, operation of the dasher plate 70 being initiated to cause additional overflow of the warm water from the compartment 61. At this time, the control cam C1 effects operation of the control switch S1 to bring about energization of the cold water solenoid 94, whereby the inlet valve mechanism 89 is governed to supply cold water to the compartment 61 for a time interval of two minutes while operation of the dasher plate 70 is continued. This cold water overflow step comprises a time

duration of two minutes, wherein any curds or scum is overflowed from the compartment 61 into the overflow conduit 83.

This step also comprises a deep cold water overflow rinsing step; and at the conclusion of this step, a drain step of four minutes is carried out followed by a squeeze step of one minute. Then a squeeze hold step of four minutes is effected, whereby excess rinse water is squeezed by the operated diaphragm 58 from the clothes contained in the compartment 61. Finally, a release step of $\frac{1}{2}$ minute is carried out and then the operating shaft 239 of the program selector switch 237 is returned to its "off" position. Thus the total time interval of the automatic cycle of the machine 10 that is governed by the timer motor 250 comprises thirty-six minutes; and normally the compartment 61 may be filled with initial wash water in a time interval of approximately two minutes, whereby the over-all semi-automatic cycle of the machine 10 may comprise a time interval of approximately thirty-eight minutes.

In the foregoing description of the operation of the machine 10 in conjunction with the semi-automatic control network disclosed in Fig. 8, the details of the operations of the various component elements of the electric circuit and the machine 10 have been omitted in the interest of brevity as it will be understood that the operations thereof are in no way essentially different from that of the same elements in the manual control circuit network described fully in conjunction with Fig. 7.

In view of the foregoing it is apparent that there has been provided a portable clothes washing machine that is especially suitable for use in apartments, or the like; which machine is of rugged and economical construction and arrangement and that embodies both washing and water extracting facilities, and is of efficient operation and of attractive appearance and design. Also, it will be understood that the improved construction and arrangement of the water extracting facility, including the movable diaphragm, in combination with the washing facility, including the unidirectionally rotated dasher plate, lends itself particularly well to both manual control and semi-automatic control, as well as fully automatic control, in a ready manner involving a simplified electric control network. Finally, it will be appreciated that the arrangement comprising the compressed air storage tanks increases the operating efficiency of the machine in that the compressed air may be stored for subsequent use during portions of the cycle of operation of the machine in which there are no heavy loads otherwise imposed upon the electric drive motor, whereby there is distributed more uniformly throughout the cycle of the machine the loads upon the electric drive motor.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a clothes washing machine including a tub adapted to contain clothes and wash liquid, mechanism operative to produce a washing action upon the clothes in said tub, means for selectively controlling the draining of the wash liquid from said tub, a flexible diaphragm ar-

ranged in said tub and movable from a normal position into an operated position to produce a squeezing action upon the clothes in said tub in order to express the wash liquid therefrom, and means defining a chamber adjacent to said diaphragm and adapted to receive fluid under pressure in order to move said diaphragm from its normal position into its operated position; the combination comprising a storage tank, a compressor operative to compress air and to deliver it under pressure into said storage tank, an electric motor, first control means for selectively operating said mechanism from said motor, pressure responsive means controlled by the pressure of the air in said storage tank for selectively operating said compressor from said motor to maintain substantially a predetermined pressure of the air in said storage tank, valve means selectively operative to connect said chamber to said storage tank and to the atmosphere, and second control means for selectively operating said valve means, the volume of said storage tank and the volume of said chamber when said diaphragm is in its operated position being so correlated that said predetermined pressure of the air in said storage tank is substantially productive of a desired squeezing pressure of the air in said chamber when said chamber is connected to said storage tank.

2. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position into an operated position to produce a squeezing action upon the clothes in said tub in order to express the wash liquid therefrom, and means defining a chamber adjacent to said diaphragm and adapted to receive fluid under pressure in order to move said diaphragm from its normal position into its operated position; the combination comprising a storage tank, a compressor operative to compress air and to deliver it under pressure into said storage tank an electric motor, means for selectively operating said mechanism from said motor, pressure responsive means for selectively operating said compressor from said motor to maintain substantially a first predetermined pressure of the air in said storage tank, and valve means for selectively connecting said chamber to said storage tank and to the atmosphere, said diaphragm in its operated position producing a predetermined desired squeezing action upon the clothes in said tub in response to a second predetermined pressure of the air in said chamber, the volume of said storage tank and the volume of said chamber when said diaphragm is in its operated position being so correlated that the pressure of the air in said storage tank falls from said first predetermined pressure substantially to said second predetermined pressure in response to the connection of said chamber to said storage tank and upon the consequent equalization of the pressures of the air therein.

3. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position

into an operated position to produce a squeezing action upon the clothes in said tub in order to express the wash liquid therefrom, and means defining a fluid-tight chamber adjacent to said diaphragm, said diaphragm being moved from its normal position into its operated position in response to the supply of fluid into said chamber and being moved from its operated position into its normal position in response to the discharge of fluid from said chamber; the combination comprising a storage tank, a compressor operative to compress air and to deliver it under pressure into said storage tank, an electric motor, first control means for selectively operating said mechanism from said motor, pressure responsive means controlled by the pressure of the air in said storage tank for selectively operating said compressor from said motor to maintain substantially a predetermined pressure of the air in said storage tank, a first valve operative to connect said storage tank to said chamber in order to supply air thereto, a second valve operative to connect said chamber to the atmosphere in order to discharge air therefrom, and second control means for selectively operating said first and second valves, the volume of said storage tank and the volume of said chamber when said diaphragm is in its operated position being so correlated that said predetermined pressure of the air in said storage tank is substantially productive of a desired squeezing pressure of the air in said chamber when said storage tank is connected to said chamber.

4. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position into an operated position to produce a squeezing action upon the clothes in said tub in order to express the wash liquid therefrom, and means defining a fluid-tight chamber adjacent to said diaphragm, said diaphragm being moved from its normal position into its operated position in response to the supply of fluid into said chamber and being moved from its operated position into its normal position in response to the discharge of fluid from said chamber; the combination comprising a storage tank, a compressor operative to compress air and to deliver it under pressure into said storage tank, an electric motor, first control means for selectively operating said mechanism from said motor, pressure responsive means controlled by the pressure of the air in said storage tank for selectively operating said compressor from said motor to maintain substantially a predetermined pressure of the air in said storage tank, a first valve operative to connect said storage tank to said chamber in order to supply air thereto, a second valve operative to connect said chamber to the atmosphere in order to discharge air therefrom, second control means for selectively operating said first and second valves, and a pressure responsive relief valve connected between said chamber and the atmosphere and controlled by the pressure of the air in said chamber in order to limit the pressure of the air therein so as to limit the squeezing action produced by said diaphragm upon the clothes in said tub, the volume of said storage tank and the volume of said chamber when said diaphragm is in its operated position being so correlated that said predetermined pres-

sure of the air in said storage tank is substantially productive of a desired squeezing pressure of the air in said chamber when said storage tank is connected to said chamber.

5. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position into an operated position to produce a squeezing action upon the clothes in said tub in order to express the wash liquid therefrom, and means defining a chamber adjacent to said diaphragm and adapted to receive fluid under pressure in order to move said diaphragm from its normal position into its operated position; the combination comprising a storage tank, a compressor operative to compress air and to deliver it under pressure into said storage tank, an electric motor, means for operating said motor, a first clutch arranged between said motor and said mechanism, first control means for selectively engaging and disengaging said first clutch, a second clutch arranged between said motor and said compressor, pressure responsive means controlled by the pressure of the air in said storage tank for selectively engaging and disengaging said second clutch to maintain substantially a predetermined pressure of the air in said storage tank, valve means selectively operative to connect said chamber to said storage tank and to the atmosphere, and second control means for selectively operating said valve means, the volume of said storage tank and the volume of said chamber when said diaphragm is in its operated position being so correlated that said predetermined pressure of the air in said storage tank is substantially productive of a desired squeezing pressure of the air in said chamber when said chamber is connected to said storage tank.
6. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position into an operated position to produce a squeezing action upon the clothes in said tub in order to express the wash liquid therefrom, and means defining a fluid-tight chamber adjacent to said diaphragm, said diaphragm being moved from its normal position into its operated position in response to the supply of fluid into said chamber and being moved from its operated position into its normal position in response to the discharge of fluid from said chamber; the combination comprising a storage tank, a compressor operative to compress air and to deliver it under pressure into said storage tank, an electric motor, first control means for selectively operating said mechanism from said motor, pressure responsive means controlled by the pressure of the air in said storage tank for selectively operating said compressor from said motor to maintain substantially a predetermined pressure of the air in said storage tank, a first valve operative to connect said storage tank to said chamber in order to supply air thereto, a second valve operative to connect said chamber to the atmosphere in order to discharge air therefrom, a controller having three positions and operative into its first position to operate said first and second

valves into their respective open and closed positions and operative into its second position to operate said first and second valves into their closed positions and operative into its third position to operate said first and second valves into their respective closed and open positions, and second control means for selectively operating said controller into its different positions, the volume of said storage tank and the volume of said chamber when said diaphragm is in its operated position being so correlated that said predetermined pressure of the air in said storage tank is substantially productive of a desired squeezing pressure of the air in said chamber when said storage tank is connected to said chamber.

7. In a clothes washing machine including a tub adapted to contain clothes and wash liquid, mechanism operative to produce a washing action upon the clothes in said tub, means for selectively controlling the draining of the wash liquid from said tub, a flexible diaphragm arranged in said tub and movable from a normal position into an operated position to produce a squeezing action upon the clothes in said tub in order to express the wash liquid therefrom, and means defining a chamber adjacent to said diaphragm and adapted to receive fluid under pressure in order to move said diaphragm from its normal position into its operated position; the combination comprising a storage tank, a compressor operative to compress air and to deliver it under pressure into said storage tank, an electric motor, first control means for selectively operating said mechanism from said motor, pressure responsive means controlled by the pressure of the air in said storage tank for selectively operating said compressor from said motor to maintain sub-

5
